INVENTOR

Waldo V. Snyder

UNITED STATES PATENT OFFICE.

WALDO V. SNYDER, OF CANTON, OHIO.

PLOW-CLEVIS.

SPECIFICATION forming part of Letters Patent No. 325,575, dated September 1, 1885.

Application filed April 28, 1885. (No model.)

To all whom it may concern:

Be it known that I, WALDO V. SNYDER, a citizen of the United States, residing at Canton, in the county of Stark and State of Ohio, 5 have invented certain new and useful Improvements in Plow-Clevises; and I do hereby declare that the following is a full, clear, and exact description of the same, reference being had to the annexed drawings, making a part 10 of this specification, and to the letters and figures of reference marked thereon, in which—

Figure 1 is a perspective view showing the clevis locked to the crown-head. Fig. 2 is a perspective view showing the clevis unlocked 15 and detached from the crown-head.

The present invention relates to that class of clevises designed to be attached to the forward end of a plow-beam; and its nature consists in the different parts and combination of 20 parts hereinafter described, and particularly pointed out in the claim.

Similar letters of reference indicate corresponding parts in each figure of the drawings.

In the accompanying drawings, A represents the plow-beam, to the forward end of 25 which is attached in the ordinary manner the crown-head B, said crown-head being provided with any desired number of cogs, b, arranged substantially as shown in the drawings.

30 The clevis C is substantially of the form shown in the drawings, and is attached to the beam A, as shown. The rear ends of the

clevis are provided with the slots a, through which pass the bolt D, as seen in the drawings. To the clevis C is pivoted the latch E, 35 which is substantially of the form shown, and is provided at its rear end with the projection d, which is for the purpose of holding the latch in the position shown in Fig. 1.

In use the latch E is raised, as shown in 40 Fig. 2, when the clevis C can be forced back, thereby disengaging the projections F from the cogs b, when the clevis can be placed in any desired position within the limits of the crown-head, when the clevis is brought forward until the projections F are engaged with the cogs b and the latch placed in the position 45 shown in Fig. 1, thereby securely locking the clevis in the position shown in said Fig. 1.

Having now fully described my invention, 50 what I claim as new, and desire to secure by Letters Patent, is—

The combination, with the clevis C, provided with the latch E and the slots a, of the cogs b and the projection F, substantially as and for 55 the purpose set forth.

In testimony that I claim the above I have hereunto subscribed my name in the presence of two witnesses.

WALDO V. SNYDER.
